EGG TONGS

Paul L. Jones, Lakegrove, Oreg.

Application May 21, 1951, Serial No. 15,258

Term of patent 14 years

(Cl. D44—4)

To all whom it may concern:

Be it known that I, Paul L. Jones, a citizen of the United States, residing at Lakegrove, in the county of Clackamas, and State of Oregon, have invented a new, original, and ornamental Design for Egg Tongs, of which the following is a specification, reference being had to the accompanying drawing, forming a part thereof.

In the drawing:

Figure 1 is a top plan view of egg tongs, showing my new design.

Figure 2 is a side elevation of Figure 1.

Figure 3 is an end view taken from the left of Figure 2.

I claim:

The ornamental design for egg tongs, as shown.
PAUL L. JONES.
